JAMES A. MARINE, OF MOORESVILLE, INDIANA, ASSIGNOR TO HIMSELF AND ALLEN T. MANKER, OF SAME PLACE.

Letters Patent No. 88,884, dated April 13, 1869.

IMPROVEMENT IN ATTACHING HOES TO THEIR HANDLES.

The Schedule referred to in these Letters Patent and making part of the same.

To whom it may concern:

Be it known that I, JAMES A. MARINE, of Mooresville, in the county of Morgan, in the State of Indiana, have invented a new and improved Mode of Attaching Hoes to their Handles; and I do hereby declare that the following is a full and exact description thereof, reference being had to the accompanying drawings, and to the letters of reference marked thereon.

My invention relates to a new method of attaching hoes, or other tools, to their handles; and

It consists in a combination of devices which accomplish the object; and

It also further consists in the means of changing the angle which the hoe or other thing may have with relation to the handle.

To enable others skilled in the art to make and use my invention, I will proceed to describe its construction and operation.

Figure 1 is a perspective view of the hoe.

Figure 2 is a horizontal view of section of same.

Figure 3 is a perspective view of the ferrule.

Figure 4 is an upright sectional view of the hoe.

Figure 5 is a view of the hoe as cut from the plate; and

Figure 6 is a perspective view of the block to change the angle of hoe.

In the drawings—

A represents the blade of the hoe, cut from a plate of steel, and has screw-bolt hole, a' , and lug-holes, $d d'$, made therein.

B is a metal ferrule on end of handle C, and has lugs $d' d'$, as seen in fig. 3, which enter holes $d d'$, in plate A.

D is a metal block, for changing the angle which the blade of the hoe shall have with relation to its handle.

This block has lugs d' , which, when used, enter the hole d in the blade; also a projection, e' , which fits in slot e , on ferrule B, and assists in holding it in position when the angle is changed.

On this block are made two or more notches, $o o'$, which have such relation to ferrule B' that it can be changed in its relative position with ferrule as seen in fig. 6.

a is a screw-bolt, which passes through washer c on the outside of the hoe, through hole a' , in the hoe-blade A, into a longitudinal hole in the end of the handle, and into the round metal nut b , as seen in fig. 2; or if the changeable or angular nut D is used, then it passes through said nut, or block, into the hole in the end of the handle and nut b , as seen in fig. 4.

The operation of attaching and changing the angle of the hoe is simple and obvious, as fig. 1 represents the hoe when the parts are together and fixed for the hoe to be unchanged in its position, as seen in fig. 2, but when it is desired to change the angle of the hoe the screw-bolt a is withdrawn and the hoe-plate and ferrule B, as seen in figs. 1 and 2, detached, and the ferrule seen in fig. 4, without the lugs $d' d'$, is put on the handle, then nut, or block D is inserted in the ferrule, which extends beyond the end of the handle, and into the desired notch, to give the proper angle, then the blade of the hoe is placed on nut D, the lugs $d' d'$ entering holes $d d'$, when the screw-bolt and washer c are put in position, and screw-bolt turned down on to washer c , and holding the hoe firmly in position.

I am aware that screw-bolts, washers, and screw-nuts have been used for the purpose of attaching hoes or other tools to their handles. None of these devices, of themselves, do I claim, but having thus described my invention,

What I claim, and desire to secure by Letters Patent, is—

1. The combination of the screw-bolt a , washer c , nut b , loose ferrule B, having lugs $d' d'$ and handle C, with the hoe-blade A, when constructed and arranged in the manner substantially as described.

2. The nut, or block D, when constructed to operate in the manner and for the purpose described.

3. The combination of the screw-bolt a , washer c , loose ferrule B, without $d' d'$ and handle C, with the blade A, all constructed and arranged in the manner substantially as described.

J. A. MARINE.
